SETTS, A CORPORATION OF MASSACHUSETTS.

SHUTTLE-BOX TENSION-CONTROLLING MECHANISM FOR LOOMS.

Application filed December 3, 1924. Serial No. 753,611.

To all whom it may concern:

Be it known that we, CLARE H. DRAPER and JONAS NORTHROP, citizens of the United States, residing at Hopedale, in the county of Worcester and Commonwealth of Massachusetts, have invented certain new and useful Improvements in Shuttle-Box Tension-Controlling Mechanism for Looms; and we do hereby declare the following to be a full, clear, and exact description of the invention, such as will enable others skilled in the art to which it appertains to make and use the same.

The present invention relates to an improvement in shuttle box tension controlling mechanism for looms.

The object of the invention is to reorganize and improve shuttle box tension controlling mechanism for looms, and particularly for weft replenishing looms of the bobbin changing type. The invention consists in the loom hereinafter described and particularly defined in the claims.

In the accompanying drawings illustrating the preferred form of the invention, Fig. 1 is a sectional elevation of the lay and associated parts; Fig. 2 is a detail showing one of the parts; and Figs. 3 and 4 illustrate a modified form of the invention hereinafter referred to, in which Fig. 3 is a section on the line 3—3, Fig. 4.

The illustrated embodiment of the invention is described as follows: The lay 10 is supported on the swords 11 provided with the shuttle box 12 adapted to contain a shuttle. The shuttle binder 14 is of the usual form, and is activated by the binder fingers 15 to cause pressure to be exerted upon the shuttle in the box. The shuttle fingers are mounted on the arms 16 of the dagger shaft 17 mounted in the brackets on the lay in the usual manner. The dagger 18 is carried by the dagger shaft 17 and adapted to engage the steel 19 of the frog 20 in the usual manner. An inertia arm 21 is secured to the dagger shaft 17, as shown in Fig. 2, and carries the weight 22 secured to it. The hub 23 of the inertia arm is provided with a dagger stop 24 adapted to engage the plate 25 on the under side of the lay 10 for the purpose of preventing overthrow of the dagger as is usual.

The right hand side of Fig. 1 is the front of the loom, and the lay is therefore shown

at or near its back center position with no 55 shuttle in the box. The movements of the lay backward and forward cause variations of pressure to be exerted upon the binders by the binder fingers owing to the weight 22 on the inertia arm. Thus, starting from 60 front center, as the lay moves rearwardly, rearward motion is imparted to the inertia arm by the lay, and the inertia of the weight 22 causes it to take up the accelerating rearward movement of the lay more slowly than 65 the lay, with the result that during the movement of the lay from front center to top center, the inertia arm relieves the pressure of the dagger fingers on the binders. So, therefore, the shuttle box tension decreases 70 from front center to top center. Another way of putting it would be to say that the inertia arm accelerates more slowly than the lay, and therefore tends to reduce the pressure of the binder fingers on the binders 75 during the first part of the rearward movement of the lay. This results in applying a diminished shuttle box tension before the picking point, which is reached a little before top center, so that the shuttle is held 80 with less friction during picking. From top center to back center the velocity of the lay in its backward movement is decreasing, and in consequence the inertia of the inertia arm tends to increase the shuttle tension during 85 this portion of the movement of the lay. At the back center the lay comes to rest and the tension on the shuttle binders is greater than it was at the front center when it began to move rearwardly. Upon passing the back 90 center the velocity of the lay is accelerated in forward movement, and the inertia of the inertia arm, located as it is below the center of the dagger shaft, tends to cause the dagger fingers to bear upon the shuttle binders with 95 a pressure decreasing as the velocity of the latter decreases. That is to say, the shuttle tension decreases from back center to bottom center. During this time the shuttle is received in the shuttle box. From bottom 100 center to front center, inasmuch as the velocity of the lay is decreasing, the inertia of the weight tends to decrease the pressure of the dagger fingers on the shuttle binders, with the result that at the front center the pressure of the shuttle binders on the shuttle is considerably less than when the lay began 105 its rearward movement from front center.

Between the time when the lay comes to rest and when it starts rearwardly ¹⁰ the pressure on the binders increases. At the back center between the time when the lay comes to rest and it again starts forward, the pressure of the shuttle binders on the shuttle decreases.

It should be remarked that the precise variations in shuttle tension due to the use ¹⁵ of the inertia arm for varying the shuttle tension are governed by a large number of elements and cannot be defined with precise definiteness. When the direction of motion of the lay changes, as at front center and back center, the action of the weight arm on the binders obviously changes. The change is probably not great at this point, but the principal change in pressures exerted by the binder fingers on the shuttle ²⁰ occurs just beyond top center, and this contributes to secure the variations in the shuttle box tensions which are desirable. Thus, when the lay starts from back center forward, the crank shaft is moving forward slowly at first and then more rapidly as the angularity of the crank increases, as a result of which the increased pressure of the binders on the shuttle is greatest at first and decreases with increasing angularity so ²⁵ that the binder pressure reaches a minimum at the time the lay reaches the end of its forward movement.

The arrangement secures a diminished shuttle tension at picking, an increased shuttle tension at boxing, and a relieved shuttle tension at or near front center, and therefore during the time of bobbin transfer, which occurs, of course, slightly before front center. These variations in shuttle box ³⁰ tension contribute to the good operation of a loom, and particularly a weft replenishing loom of the bobbin changing type.

In Fig. 4 is shown a construction in which the hub 33 of the inertia arm 21 is loosely mounted on the dagger shaft 17, being held from endwise movement in one direction by the collar 34, and in the other direction by the collar 35. The latter carries the dagger stop 24. Limited rotational movement of the hub 33 on the dagger shaft 17 is permitted owing to the fact that the collar 35 and the hub 33 are shouldered as shown at 36, and have a spring 37 (see Fig. 3) between two ears 38 and 39 which are formed on the collar 35 and hub 33 respectively. Viewing the structure as shown in Fig. 1, and assuming it to be provided with the form of inertia arm and support illustrated in Figs. 3 and 4, it will be seen that when the lay moves forward the lag of the weight ³⁵ 22 tends to compress the spring 37, which pressure is thereby exerted through that spring upon the collar 35 of the dagger shaft 17. Thus, the inertia of the weight is yieldingly applied in one direction to the

dagger shaft. This secures a more gradual decrease of the shuttle box tension during movement from back center to bottom center than during movement from front center to top center.

Having thus described the invention, what is claimed is:

1. Shuttle box tension controlling mechanism for looms having, in combination, a lay, a shuttle box, a binder, a dagger shaft ⁷⁰ 75 on the lay, binder fingers on the dagger rod, and an inertia arm on the dagger rod provided with a weight below the dagger rod.

2. Shuttle box tension controlling mechanism for looms having, in combination, a lay having a shuttle box, a binder for the shuttle box, inertia controlled means for applying pressure to the binders acting to decrease the binder pressure at the picking point. ⁸⁰ ⁸⁵

3. Shuttle box tension controlling mechanism for looms having, in combination, a lay having a shuttle box, a binder for the shuttle box, an inertia controlled tension applying means having provision for increasing the tension of the binder on the shuttle during boxing. ⁹⁰

4. Shuttle box tension controlling mechanism for weft replenishing looms of the bobbin changing type having, in combination, a lay provided with a shuttle box, a binder for the shuttle box, and an inertia controlled tension applying means acting to decrease the shuttle box tension at front center to facilitate bobbin transfer. ¹⁰⁰

5. Shuttle box tension controlling mechanism for looms having, in combination, a lay provided with a shuttle box, a binder for the shuttle box, inertia controlled pressure applying means for the binders acting to decrease the binder pressure during picking and increase it during boxing. ¹⁰⁵

6. Shuttle box tension controlling mechanism for weft replenishing looms of the bobbin changing type having, in combination, a lay provided with a shuttle box, binders, and inertia controlled pressure applying means acting to decrease the binder pressure during picking and also to decrease it during bobbin transfer. ¹¹⁰ ¹¹⁵

7. Shuttle box tension controlling mechanism for weft replenishing looms of the bobbin changing type having, in combination, a lay provided with a shuttle box, binders for the shuttle box, inertia controlled pressure applying means acting to increase the binder pressure during boxing and to decrease it during the time of bobbin transfer. ¹²⁰

8. Shuttle box tension controlling mechanism for weft replenishing looms of the bobbin changing type having, in combination, a lay provided with a shuttle box, a binder, inertia controlled pressure applying means for the binders acting to increase the binder pressure from front center to top center, to ¹²⁵ ¹³⁰

increase it from top center to back center, to decrease it from back center and to bottom center, to decrease it from bottom center to front center.

5. Shuttle box tension controlling mechanism for looms having, in combination, a lay provided with shuttle boxes, binders for the boxes, a dagger shaft mounted on the lay, binder fingers carried by the dagger shaft 10 and projecting upwardly therefrom to engage the binders, and an inertia arm mounted on the dagger shaft extending downwardly therefrom and provided with a weight.
10. Shuttle box tension controlling mechanism for looms having, in combination, a lay provided with shuttle boxes, binders for the shuttle boxes, inertia controlled pressure ap-

plying means for the binders having yielding means for transmitting increased pressure to the binders, and positive means for 20 transmitting decreased pressure to the binders.

11. Shuttle box tension controlling mechanism for weft replenishing looms of the bobbin changing type having, in combination, a 25 lay provided with a shuttle box, binders for the shuttle box, inertia controlled pressure applying means acting to apply pressure to the binders greatest in amount at the earliest time of arrival of the shuttle in the box and 30 less and less in amount the later the time of shuttle arrival.
